SELECTIVE TRANSMISSION OF ELECTRIC WAVES

Filed July 26, 1922

Inventor
Harald J. Vennes
by E. V. Briggs Atty.

UNITED STATES PATENT OFFICE.

HARALD J. VENNES, OF WESTMOUNT, QUEBEC, CANADA, ASSIGNOR TO WESTERN ELECTRIC COMPANY, INCORPORATED, OF NEW YORK, N. Y., A CORPORATION OF NEW YORK.

SELECTIVE TRANSMISSION OF ELECTRIC WAVES.

Application filed July 26, 1922. Serial No. 577,493.

To all whom it may concern:

Be it known that I, HARALD J. VENNES, a citizen of the United States of America, residing at Westmount, in the Province of Quebec, Dominion of Canada, have invented certain new and useful Improvements in the Selective Transmission of Electric Waves, of which the following is a full, clear, concise, and exact description.

10 This invention relates to the selective transmission of electric waves and particularly to the prevention of interference due to stray or leakage currents in such a system. This invention provides an improved arrangement for associating electric wave or alternating current transmitting and receiving circuits with a transmission medium or line. In a more limited aspect it provides an improved arrangement for associating 20 carrier wave transmitting and receiving circuits with a transmission medium or line.

For a general description of carrier systems, reference may be had to a paper entitled "Carrier current telephony and telegraphy," by Messrs. Colpitts and Blackwell, published in the Journal of the American Institute of Electrical Engineers, for April, May and June, 1921. In the systems therein described, the carrier terminal apparatus is 30 connected to the carrier line through a balanced transformer, so that the transmitting and receiving circuits are conjugately connected to the line with respect to one another, a balancing network being used to 35 balance the impedance of the line. A more simple arrangement consists in directly connecting the transmitting and receiving circuits to the transmission line, and preferably to employ distinctive frequencies for 40 transmissions in opposite directions. Such an arrangement, however, is often troublesome due to stray or leakage currents arising from the unbalanced arrangement of the terminal circuits.

45 An object of this invention is to provide a simple terminal arrangement for electric wave transmission systems, which is free from noise and interference due to stray or leakage currents in the system, but which 50 still makes use of a simple connection between the terminal apparatus and the transmission medium or line. Another object is to provide such a simple arrangement for

carrier current signaling systems. Other objects of the invention will become apparent as the description proceeds.

The term transmission medium as used in this specification is to be understood to embrace a transmission circuit including both metallic conductors and other media for the transfer of electrical energy between two points. The electrical midpoint of such medium or of a transmission line refers to the positions at which the potential is midway between the desired driving potentials. For example, if a certain driving potential is applied between the line wires of a transmission line, the electrical midpoint of the line would be at the point where the potential drop from one wire to said midpoint is equal to the potential drop from said midpoint to the other wire.

In the preferred embodiment of the invention, a shielded transformer is connected between a common carrier receiving circuit and a carrier transmission line, while a common transmitting circuit is connected to the electrical midpoint of the line side of the transformer. A plurality of carrier receiving branches are connected to the common receiving circuit on the one hand, and a plurality of carrier transmitting branches, to the transmitting circuit on the other. An electrostatic shield which is maintained at ground potential is located between the line winding and the station winding of the transformer. The invention, however, is applicable to a terminal station comprising only one transmitting and one receiving branch.

Referring now to the drawing which shows the preferred embodiment of the invention, a carrier transmission line ML is connected to a carrier transmitting circuit TC, and a carrier receiving circuit RC by means of a two winding transformer 5. A high pass filter HPF is inserted between the transformer 5 and the line ML to allow the passage of carrier currents, but to substantially prevent the passage of currents having essential frequencies in the voice range or below. This filter is of the general type described in the patent to G. A. Campbell, No. 1,227,113, May 22, 1917.

An ordinary telephone line TL may also be connected to the transmission line ML.

A low pass filter LPF of the general type described in the above mentioned Campbell patent is inserted in the line TL to allow the passage of currents of essential voice frequencies and lower frequencies and to prevent the flow of carrier currents to the line TL.

A transmitting branch comprising a source O of carrier frequency waves, modulator M, and a transmitting band filter SBF, is connected to the transmitting circuit TC. A receiving branch comprising a receiving band filter RBF, demodulator D, demodulator amplifier A, and a low pass voice frequency filter VF, is connected to the receiving circuit RC. A low frequency line L is associated with the transmitting and receiving branches by means of a balanced transformer 6. A low frequency network LN balances the line L, so that the transmitting and receiving channels are conjugately connected to the line L with respect to one another.

The oscillator O, modulator M, detector D, and detector amplifier A, are preferably of the well known vacuum tube types, but any other suitable type of apparatus may be substituted therefor. The band filters SBF and RBF are of the general type described in the Campbell patent hereinbefore mentioned, differing from each other only in the constants of the inductance and capacity elements, the values of which depend upon the band of frequencies which it is desired to transmit.

Other transmitting and receiving branches may be connected to the transmitting circuit TC, and to the receiving circuit RC, as indicated by blocks 7, 8 and 9, 10 respectively. In the preferred system, each band filter passes a distinctive band of frequencies, and the transmitting frequencies as a group occupy a different range from the receiving frequencies as a group. For example at a given terminal station carrier frequencies of 6, 9 and 12 kilocycles might be used for transmitting and carrier frequencies of 15, 18 and 21 kilocycles, for receiving. At the distant station the group of higher frequencies would be used for transmitting and the group of lower frequencies, for receiving. The end sections of these band filters, adjacent to the transmission line ML are of low impedance to all frequencies, except those which the individual filter is designed to pass to or from the line ML as the case may be. These end sections of all of the transmitting filters are connected in series with each other and with the transmitting circuit TC. Likewise the end sections of all of the receiving band filters are connected in series with each other and with the receiving circuit RC.

In the preferred system, a grouping filter GF is inserted in the receiving circuit RC,

between the receiving band filters and the transformer 5. This filter is adapted to pass the range of frequencies used for reception at this station and to substantially exclude the range of frequencies used for transmission. Likewise, a grouping filter TGF (shown in dotted lines, since it is not actually used in the preferred system) may be inserted in the transmitting circuit TC to freely transmit the frequencies employed for transmitting, and to substantially exclude the frequencies employed for reception at this station. Both the filter GF and the filter TGF may be omitted, if the band filters in the several transmitting and receiving branches provide satisfactory discrimination between the transmitting and receiving frequencies. These filters are likewise of the general type described in the aforementioned Campbell patent. If the grouping filters GF and TGF are both omitted, it is obvious that the grouped arrangement of transmitting and receiving frequencies need not be used. The so-called staggered frequency arrangement may be found preferable.

The transformer 5, has been described as a two winding transformer. By this is meant that in respect to its transforming action, it may be treated as having only two windings, one called a station winding to which the receiving circuit RC is connected, and the other a line winding to which the transmission line ML is connected. In fact, however, the line winding at least is composed of two electrically identical windings, so that the transmitting circuit TC may be connected in series therewith, and to the electrical midpoint thereof. It is immaterial how many windings are actually employed, so long as they are connected up into groups in such a way that one group forms a station winding and the other group a line winding with means to connect the transmitting circuit to its electrical midpoint.

For the best results, an electrostatic shield 11 is placed between the station and line windings and this shield is maintained at ground potential. This grounded shield furnishes a short circuit path to ground for any unbalance currents originating in the line ML or any other of the circuits connected to the line winding of transformer 5. Such unbalance currents would otherwise find their way into the receiving circuit RC, due to the capacity between the line and station windings, and would cause interference and noise.

In a complete carrier system another station similar to the one described and shown in the drawing, would be provided at the distant end of the transmission line ML. This station would be so arranged that the transmitting branches at the station described, would cooperate with the receiving branches at the distant station, and the

transmitting branches at the distant station would cooperate with the receiving branches at the station shown. The method of operation will not be described, since it is obvious from the Colpitts and Blackwell paper hereinbefore mentioned.

It should be noted that since the end section of the grouping filter GF, if such a filter is used, or the end sections of the receiving band filters if no grouping filter GF is employed, are of low impedance to the transmitted frequencies, and therefore act as a short circuit for the station winding of the transformer 5, and consequently the transformer 5 offers small impedance to the transmitted frequencies. This follows from well known transformer theory. The self inductance of the primary or line winding is largely neutralized by the magnetic effect of the short circuit current in the secondary or station winding, so that the primary impedance is greatly reduced over what it would be with an open circuited secondary. Also, the end section of the transmitting grouping filter TGF or the end sections of the transmitting band filters, if the filter TGF is not employed, are of low impedance to the received frequencies, and therefore function as a direct low impedance connection between the electrical midpoint terminals of the line winding for these frequencies. Thus a balanced terminal circuit is obtained with very little decrease in transmission efficiency, over what would be obtained were the transmitting and receiving circuits directly connected to the transmission line ML.

The invention has been described in its embodiment in a multiplex carrier telephone system, but its use is not limited to that specific system.

What is claimed is:

1. An alternating current system comprising a transmission line, a transmitting circuit for impressing alternating current upon said line, another circuit for receiving alternating current from said line, and a transformer having a line winding and a station winding, said receiving circuit being connected to said station winding, said line winding being connected to said line, and said transmitting circuit being connected in series with said line winding at its electrical midpoint.

2. A carrier terminal system comprising a transmitting circuit, a receiving circuit, a transmission line, and a two winding transformer having one of its windings connected to the receiving circuit, the other connected to the transmission line and the transmitting circuit connected in series with the line winding at its electrical midpoint.

3. A carrier terminal system comprising a transmitting circuit, a receiving circuit, a transmission line, a source of carrier current

of characteristic frequency for said transmitting circuit, a selective circuit adapted to pass this characteristic frequency connected between said source of carrier current and said transmitting circuit, a detector for carrier current of a different frequency, a selective circuit adapted to pass current of said different frequency connected between said receiving circuit and said detector, and a two winding transformer having one of its windings connected to the receiving circuit, the other connected to the transmission line and the transmitting circuit connected in series with the line winding at its electrical midpoint.

4. In a multiplex carrier terminal system, a transmission line, a transmitting circuit, a plurality of transmitting branches connected to said transmitting circuit, a receiving circuit, a plurality of receiving branches connected to said receiving circuit, and a transformer having a line winding and a station winding, said receiving circuit being connected to said station winding, said line winding being connected to said transmission line and said transmitting circuit being connected in series with said line winding at its electrical midpoint.

5. In a multiplex carrier telephone terminal system, a transmission line, a transmitting circuit, a plurality of transmitting branches each comprising means to modulate a characteristic carrier frequency wave in accordance with voice frequencies and a band filter adapted to transmit waves of the resulting band of frequencies, means to connect the end sections of said band filters in series with each other and with said transmitting circuit, a receiving circuit, a plurality of receiving branches each comprising means to demodulate waves of a characteristic band of frequencies and a band filter adapted to transmit waves of said characteristic band of frequencies, means to connect the end sections of said last named band filters in series with each other and said receiving circuit, and a transformer having a line winding and a station winding, said receiving circuit being connected to said station winding, said line winding being connected to said transmission line, and said transmitting circuit being connected in series with said line winding at its electrical midpoint.

6. In a multiplex carrier terminal system, a transmission line, a transmitting circuit, a plurality of transmitting branches each comprising a band filter adapted to pass a characteristic band of frequencies and having an end section of low impedance to all frequencies except those which it is adapted to transmit, means to connect said end sections in series with each other and with the transmitting circuit, a receiving circuit, a plurality of receiving branches each com-

- 4
- prising a band filter adapted to pass a characteristic band of frequencies and having end sections of low impedance to all frequencies except those which it is adapted to transmit, means to connect the end sections of said last named filters in series with each other and with the receiving circuit, and a transformer having a line winding and a station winding, said receiving circuit being connected to said station winding, said line winding being connected to said transmission line and said transmitting circuit being connected in series with said line winding at its electrical midpoint.
- 15 7. In a multiplex carrier terminal system, a transmission line, a transmitting circuit, a plurality of transmitting branches each comprising a band filter adapted to pass a characteristic band of frequencies and having an end section of low impedance to all frequencies except those which it is adapted to transmit, means to connect said end sections in series with each other and with the
- transmitting circuit, a receiving circuit, a plurality of receiving branches each comprising a band filter adapted to pass a characteristic band of frequencies and having end sections of low impedance to all frequencies except those which it is adapted to transmit, means to connect said last recited end sections in series with each other and with the receiving circuit, a transformer having a line winding and a station winding, said receiving circuit being connected to said station winding, said line winding being connected to said transmission line and said transmitting circuit being connected in series with said line winding at its electrical midpoint, and an electrostatic shield between the windings of said transformer, said shield being maintained at ground potential. 25 30 35 40

In witness whereof, I hereunto subscribe my name this 18th day of July A. D., 1922.

HARALD J. VENNES.
